US00D606028S

(12) **United States Design Patent**
Chou

(10) **Patent No.:** **US D606,028 S**
(45) **Date of Patent:** ** *Dec. 15, 2009

(54) **DIMMER SWITCH**

(75) Inventor: **Cheng-Lung Chou**, Great Neck, NY
(US)

(73) Assignee: **Leviton Manufacturing Co., Inc.**, Little Neck, NY (US)

(**) Term: **14 Years**

(21) Appl. No.: **29/327,358**

(22) Filed: **Nov. 4, 2008**

(51) LOC (9) Cl. **13-03**

(52) U.S. Cl. **D13/169**; D13/171

(58) Field of Classification Search D13/169,
D13/171; 174/66; 200/5 R, 1 B, 433, 525,

OTHER PUBLICATIONS

U.S. Appl. No. 11/559,646 filed Nov. 14, 2006 entitled, "RF Antenna Integrated into a Control Device Installed into a Wall Switch Box".

Primary Examiner—Selina Sikder

(74) Attorney, Agent, or Firm—Carter, DeLuca, Farrell & Schmidt, LLP

(57) **CLAIM**

The ornamental design for a dimmer switch, shown and described.

DESCRIPTION

FIG. 1 is a front left perspective view illustrating our new design for a dimmer switch with the broken lines showing, for illustrative purposes only, a back plate and a housing that are not part of the claimed design;

FIG. 2 is a front view thereof with the dashed lines showing the back plate;

FIG. 3 is a left side view thereof with the broken lines showing the back plate and the housing;

FIG. 4 is a right side view thereof with the broken lines showing the back plate and the housing;

FIG. 5 is a top view thereof with the broken lines showing the back plate and the housing; and,

FIG. 6 is a bottom view thereof with the broken lines showing the back plate and the housing.
